UNITED STATES PATENT OFFICE

124,034

DESIGN FOR A JAR OR SIMILAR ARTICLE

Meredith Stewart Ireys, Lancaster, Pa., assignor to Armstrong Cork Company, Lancaster, Pa., a corporation of Pennsylvania

Application September 13, 1940, Serial No. 95,012

Term of patent 14 years

To all whom it may concern:

Be it known that I, Meredith Stewart Ireys, a citizen of the United States, residing in Lancaster, county of Lancaster, Commonwealth of Pennsylvania, have invented a new, original, and ornamental Design for a Jar or Similar Article, of which the following is a specification, reference being had to the accompanying drawing, forming a part thereof, and of which—

Figure 1 is a view in elevation of the front of the jar or similar article of my invention (the jar is of generally round shape in horizontal section and the rear of the jar is substantially the same as the front); and

The dominant features of my design reside in the portion shown in solid lines.

I claim:

The ornamental design for a jar or similar article, substantially as shown and described.

MEREDITH STEWART IREYS.
